VICTOR H. BUSCHMANN, OF BALTIMORE, MARYLAND.

Letters Patent No. 77,452, dated May 5, 1868; antedated April 25, 1868.

IMPROVEMENT IN RACKS FOR BILLIARD-CUES.

The Schedule referred to in these Letters Patent and making part of the same.

TO WHOM IT MAY CONCERN:

Be it known that I, VICTOR H. BUSCHMANN, of Baltimore, county of Baltimore, and State of Maryland, have invented a new and useful Self-Opening and Closing Receptacle for Billiard-Cues and other articles; and I do hereby declare that the following is a full, clear, and exact description of the same, reference being had to the accompanying drawings, forming part of this specification, in which—

Figure 1 is a rear view of one of the receptacles of a billiard-cue rack, the cue being in place in it.

Figure 2 is a vertical section of the same, the cue being removed from it.

Figure 3 is a similar section to fig. 2, the cue being in place.

Figure 4 is a top view and section of the receptacle, with the cue in it.

Figure 5 is a front view and partial section of the receptacle, the black lines showing the position of the parts before the cue is inserted in the receptacle, and the red lines showing the position of the parts after the cue is inserted into the receptacle.

Similar letters of reference in the several figures indicate corresponding parts.

The nature of my invention consists in operating the retaining-button of the respective receptacles of a cue-rack, so as to open the cue-receptacles, by a weighted lever, and also operating it so as to close the receptacle by the weight of the cue being brought to act upon the weighted lever.

The invention, which I shall describe, is designed especially for cue-racks, but is applicable to racks used in armories for retaining rifles or guns in an upright position.

To enable others skilled in the art to make and use my invention, I will proceed to describe the same with reference to the drawings.

A represents one of the receptacles of a billiard-cue rack.

In the front of the upper cross-piece, *a*, of this receptacle I cut a semi-elliptic recess, *b*, and in the intermediate cross-piece, *c*, a circular hole, *b'*, is bored through vertically, as shown.

At one side of the recess *b* a retaining-button or stop-piece, *d*, is fastened, as shown, to a pivot-rod, *e*, which extends through to the rear edge of the cross-piece *a*, and on its terminus a link, *f*, is firmly fastened, said link being pivoted to a vertical connecting-rod, *g*, which extends down to the bottom of the receptacle, and connects, by means of a pivot, with a rocking-lever, *h*, which is arranged at right angles to the front face of the receptacle, being pivoted to lugs, *i i*, projecting up from the bottom board of the receptacle.

The construction and arrangement of the foregoing contrivance are such, that when the billiard-cue is placed upon the forward end of the lever *h*, the weight of the cue causes said end to descend from the position shown in fig. 2 to the position shown in fig. 3. This descent of the lever causes the connecting-rod *g* to rise, and, in rising, this rod moves the link *f*, and causes the pivot-rod to turn, the distance of a quarter circle, and thereby move the retaining-button or stop from the position shown in black in fig. 5 to the position shown in red in same figure. Thus, the button is thrown to a position for retaining the cue in its receptacle by the simple weight of the cue. It follows, that by removing the cue the parts will automatically assume the position they originally occupied.

The great advantage of my improvement is this: the billiard-player is saved the inconvenience and trouble of raising the cue to the top of the receptacle before he can get it into its place; for, with my arrangement, the cue-receptacle is always open, so that the cue may be inserted by a lateral and slightly downward movement through the hole in the intermediate partition, and, when the cue is inserted, its weight causes the button or stop to close the receptacle.

Claim.

So constructing a billiard-cue receptacle, that the weight of the cue, when placed therein, shall close it, and when the cue is withdrawn the receptacle will open, and remain open, for the return of the cue.

Witness my hand, in the matter of my application for a patent for a rack for billiard-cues, &c.

VICTOR H. BUSCHMANN.
